SAMPLE HOLDER AND EASEL THEREFOR

Martin Steinthal, New York, N. Y.

Application August 14, 1936, Serial No. 96,030

1 Claim. (Cl. 281—33)

This invention relates to improvements in display devices and has particular reference to a holder for samples, display cards and the like, and an easel therefor.

5 An object of the invention is to provide an improved display device of simple and practical construction wherein the body of the device consists of a holder having an intermediate supporting section to which is pivotally connected 10 two cooperating cover sections adapted to enclose samples, cards and the like within the holder, and wherein said body is further provided with an easel adapted to support the device in a position 15 in which the contents may be conveniently displayed.

The above and other objects will appear more clearly from the following detailed description when taken in connection with the accompanying drawing which illustrates a preferred embodiment of the inventive idea.

In the drawing:

Figure 1 is a perspective view of the device with one of the cover sections thereof in its open or display position.

25 Figure 2 is a vertical section therethrough, and

Figure 3 is an edge elevation, partly broken away and shown in section.

The holder of the present invention is shown as comprising an intermediate section 5 which 30 may be of cardboard or other suitable material and which is adapted to support groups of sample cards 6 or the like arranged side by side thereon. Secured to each of the side edges of said section 5 is a spiral binder 7 to which the cards 6 of 35 one group is connected so that said cards may be individually turned. Each binder 7 also constitutes a hinge connection between said section 5 and a cover section 8 so that the latter sections may be conveniently swung to open and closed 40 positions, as indicated in Figure 1, said sections 8 being made of the same material as the section 5. When closed, each section 8 covers the group 45 of cards disposed on the adjacent side of the supporting section 5, and said sections 8 lie in the same plane with their free side edges meeting, but not overlapping, so that either one of the cover sections may be swung to open position without interfering with the other. The front 50 of each section 8 may be in the nature of a frame provided with an opening 9 having a transparent cover 10 beneath which may be placed a sheet 11 containing a suitable illustration or advertising indicia. Said sections 8 may be of equal 55 or different sizes depending upon the size of the sample cards 6, but in any event the combined

areas of the sections is equal to that of the intermediate supporting section 5.

In order to support the holder proper in an inclined position as shown in Figures 1 and 2, the device is provided with an easel. This easel is 5 shown in its preferred form as comprising a backing sheet 12 which may be of cardboard or the like and which is of slightly less area than the section 5 to which it is adhesively secured on the back surface thereof. A second sheet 13, of 10 the same length as the sheet 12 but of considerably less width, is secured along the upper edge of the latter sheet, and has pivotally connected to its lower edge the supporting sheet 14, the combined areas of the sheets 13 and 14 being 15 equal to that of the sheet 12. Connecting the bottom edge of the sheet 12 with that of the sheet 14 is a bottom for the easel consisting of the two hingedly connected sections 15 and 16 which are adapted to fold inwardly, as indicated 20 in dotted lines in Figure 2, when the device is not in use. To pivotally connect the sheets 13 and 14 with each other and to similarly connect the sections 15 and 16 with the sheets 14 and 12, respectively, a single outer flexible lining 17 of 25 cloth, paper or other fabricated material is secured to the outer surfaces of the various elements in covering relation thereto, with the upper and lower edges of said lining interposed between the section 5 and the backing sheet 12, 30 as indicated at 18. A single inner lining 19 is also provided for the sheet 14 and sections 15 and 16 of the easel bottom and, as will be noted, this inner lining cooperates with the outer lining 17 in forming the hinge connection between said 35 sheet and sections, while the lining 17 also pivotally connects the sheet 14 with the sheet 13 and section 15, and the section 16 with backing sheet 12.

What is claimed is:

40 In a display device of the character described, an intermediate supporting section, two end cover sections pivotally joined to said intermediate section and foldable to closed position with their outer edges meeting in non-overlapping relation, 45 means to pivotally connect said cover sections to said intermediate section and to which articles to be displayed are pivotally connected, an easel for said device comprising a backing sheet of substantially the area of said intermediate sec- 50 tion secured to the rear surface thereof, a sec- 55 ond sheet superimposed upon said backing sheet, a supporting sheet hingedly connected to said second sheet for swinging movement toward and away from said backing sheet, said second and

supporting sheets having a combined area equal to that of said backing sheet, a bottom for said easel including two hingedly connected sections joining the lower edge of said supporting sheet with that of said backing sheet, and a single continuous outer lining for said second and supporting sheets and the sections of said bottom and

constituting the hinge connection between the last named sheets, and further forming a pivotal connection between the inner adjacent edges of said bottom sections and between the outer opposed edges of the latter and said supporting and backing sheets. 5

MARTIN STEINTHAL.
